UNITED STATES PATENT OFFICE.

ROBERT E. SHEPHARD, OF OAKLAND, CALIFORNIA.

DESIGN FOR AN AUTOMOBILE DELIVERY-BODY.

57,387.

Specification for Design.

Patented Mar. 15, 1921.

Application filed April 12, 1920. Serial No. 373,400. Term of patent 14 years.

To all whom it may concern:

Be it known that I, ROBERT E. SHEPHARD, a citizen of the United States, residing at Oakland, in the county of Alameda and State of California, have invented a new, original, and ornamental Design for Automobile Delivery-Bodies, of which the following is a specification, reference being had to the accompanying drawing, forming part thereof.

Figure 1 is a side view of an automobile delivery body showing my new design.

Fig. 2 is an end view of the same with the side doors open.

I claim:

The ornamental design for an automobile delivery body, as shown.

In testimony whereof I affix my signature.

ROBERT E. SHEPHARD.
